PROTECTIVE GUARD FOR SHOES

Louis F. Marino, Boston, Mass., assignor to George
R. Long, Boston, Mass.

Application November 10, 1939, Serial No. 303,807

12 Claims. (Cl. 36—72)

This invention relates to a guard to protect shoes during their manufacture or during their repair.

When the sole of a shoe is cemented to the upper during manufacture or repair the sole is pressed into such tight engagement with said upper that the cement or other adhesive between the two will often run out onto the upper, thereby staining or discoloring it, which requires extra labor to clean said upper or spoils it for use. To protect said upper from said cement I have provided a new and novel protective guard for the upper, which is simple to use and fully serves its purpose of protecting the upper during manufacture or repair of the shoes. I am aware that attachments for shoes intended to similarly protect the upper have been made; and it is my particular object to provide a new and novel construction of said protective guard that is much more efficient and reliable than any heretofore known, and can be placed in position on a shoe almost instantaneously and with the utmost ease.

The foregoing and other objects which will appear as the nature of the invention is better understood, may be accomplished by a construction such as is disclosed by the drawings and specification. The nature of the invention is such as to render it susceptible to various changes and modifications, and, therefore, I am not to be limited to said disclosures; but am entitled to all such changes therefrom as fall within the scope of my claims.

In the drawings:

Figure 1 is a perspective view of an incompletely shoe with my protective guard in place thereon to protect the upper, and Figure 2 is a similar perspective view showing a half sole being applied to said shoe.

Figure 3 is a perspective view of said protective guard in usable position.

Figure 4 is an enlarged detail view broken away, showing a rear end portion of my protective guard in a different position from that shown in Figure 3.

Figure 5 is a fragmentary side elevational view of the toe portion of a shoe, with my protective guard thereon shown in section.

Figure 6 is a fragmentary side elevational view of an upturned shoe toe portion showing said toe portion being brushed during a finishing operation while protected by my guard.

Figure 7 is a perspective view of an unfinished shoe that is having a whole sole applied thereto with another form of my protective guard adapt-

able for use when whole soles are applied to a shoe, and Figure 8 is a perspective view of this protective guard alone.

Figure 9 is a perspective view of my protective guard with a top cover attached thereto, and Figure 10 is a sectional view taken on the line 10—10 of Figure 9.

As illustrated my protective guard 10 when used is placed on the upper of a shoe S where it meets the sole 11 so that part of the shoe next to the outer sole 11 and a portion of the upper adjoining it is completely protected from cement C or other adhesive that may be used to unite said sole to said upper. At the upper edge of my guard 10 is a flange or slightly turned-in portion 12 clearly illustrated in Figure 5 of the drawings, which extends the full length of my guard 10 uninterrupted, in order to furnish full protection for the shoe upper where it turns inwardly and is overlaid by the outer sole 11. This flange portion 12 is made integral with and formed in the top edge of said guard 10, and by that I mean the edge that is uppermost when using said guard 10 in putting the sole on the shoe S, the latter 20 then being in the inverted position shown in Figures 1 and 2 of the drawings. Said flange portion 12 is turned in at less than a right angle to the adjoining portion of said guard, and preferably there are no openings or slits in it.

The two rear end portions 13 of my guard 10 converge towards each other somewhat, thus constricting the open end of said guard, and there is a twist in said rear portions so that the lower portion 14 of said guard 10 is turned or flares 35 outwardly while the upper portion 15 directly above turns inwardly, thereby giving a twist to said rear portions 13, as shown in the drawings, which is most desirable in obtaining a protective guard 10 that will fit all parts of the shoe upper intended to be protected. Inasmuch as my guard can be made of metal, of the spring-type, when it is placed on said shoe upper its construction is such that it tends to fit itself to the contour of the shoe upper portion intended to be protected and will tend to cling thereto. Also, by providing holes H in my guard 10 it can be mechanically held to said shoe S with nails extending therethrough.

To protect the whole front portion of the shoe upper I provide a top covering 18 preferably made of cloth which is held to said guard 10 by thread 20 that extends through holes 19 provided in said guard for this purpose. This covering 18 may extend to the back of said shoe S so as to completely cover it.

When a whole sole is to be cemented to a shoe upper I provide a longer guard having extended portions 17 which extend substantially straight and parallel to thereby cover more of the shoe upper to correspond with the longer sole, as illustrated in Figures 7 and 8 of the drawings. In the manufacture of shoes this type of guard would ordinarily be used.

My guard is likewise found useful when attaching an upper to an outer sole 11 by stitching inasmuch as the upper may be soiled by the worker if left unprotected.

What I claim is:

1. A protective guard for a shoe or the like having a turned-in portion at the upper edge of said guard that extends in solid, unbroken formation uninterruptedly around said upper edge, to the extremities thereof, the end extremity portions of said guard extending in the same general direction as the longitudinal axis of said guard.

2. A protective guard for a shoe or the like having a turned-in portion at the upper edge of said guard that extends inwardly at less than a right angle to the adjoining portion of said guard, said turned-in portion continuing to the end extremity portions of said guard.

3. A protective guard for a shoe or the like having an open end at its rear and comprising two rear end portions spaced laterally apart that converge in a direction towards said open end at a point intermediate the end extremities of said guard and then extend substantially straight to the open end extremity of said guard.

4. A protective guard for a shoe or the like having an open end at its rear and comprising two rear end portions spaced laterally apart that converge in a direction towards said open end and are distorted laterally at a point intermediate the end extremities of said guard and then extend substantially straight to the open end extremity of said guard.

5. A protective guard for a shoe or the like having an open end at its rear and comprising two rear end portions spaced laterally apart that converge in a direction towards said open end the lower portions of which are distorted outwardly and the inner portions distorted inwardly at a point intermediate the end extremities of said guard and then extend substantially straight and parallel to the open end extremity of said guard.

6. A protective guard for a shoe or the like having an open end at its rear and having a turned-in portion at the upper edge of said guard that extends inwardly at less than a right angle to the adjoining portion of said guard and extends uninterruptedly around said upper edge, said guard comprising two rear end portions spaced laterally apart that converge in a direction towards said open end and embodying a lower portion that flares outwardly and an upper portion that extends inwardly intermediate the end extremities of said guard, said rear end por-

tions extending substantially straight and parallel beyond said converging portions to the open end extremity of said guard.

5 7. A protective guard for a shoe or the like having an open end and comprising two rear end portions spaced laterally apart, each having a permanent laterally twisted portion, a lower portion of which flares outwardly and an upper portion of which directly across from and contiguous with said lower portion flares inwardly, the end extremities of said guard extending substantially parallel with each other in the same general direction as the longitudinal axis of said guard.

10 8. A protective guard for a shoe or the like having an open end and comprising two rear end portions spaced laterally apart and converging towards each other at portions in said guard intermediate the opposite end extremities thereof, the end extremity portions of said rear end portions extending substantially straight to the tip ends thereof.

20 9. A protective guard for a shoe or the like having an open end and comprising two rear end portions spaced laterally apart, each having a permanent laterally twisted portion, a lower portion of which flares outwardly and an upper portion of which flares inwardly, said guard having a turned-in portion running along the upper edge that extends inwardly from said upper portion at less than a right angle thereto.

25 10. A protective guard for a shoe or the like having an open end and comprising two rear end portions spaced laterally apart, each having a permanent laterally twisted portion, a lower portion of which flares outwardly and an upper portion of which flares inwardly, said guard having a turned-in portion running along the upper edge that extends inwardly from said upper portion at less than a right angle thereto, said turned-in portion extending in solid formation and continuously around said guard to the extremities thereof.

30 11. A protective guard for a shoe or the like having an open end at its rear and comprising two rear end portions spaced laterally apart and a front curved portion from which said rear end portions extend, the end extremity portions of said rear end portions extending substantially straight to the open end extremities of said guard.

35 12. A protective guard for a shoe or the like having an open end at its rear and comprising two rear end portions spaced laterally apart and a front curved portion from which said rear end portions extend, an intermediate part of said rear end portions being permanently twisted laterally so that portions thereof extend laterally at angles to each other, the end extremity portions of said rear end portions beyond said twisted portions being untwisted laterally and extending substantially straight to the open end extremities of said guard.

LOUIS F. MARINO.
